ROBERT M. LAMPMAN, OF ANCASTER, ONTARIO, CANADA.

FORWARD AND REVERSE GEARING MECHANISM.

1,215,664.

Specification of Letters Patent. Patented Feb. 13, 1917.

Application filed August 7, 1916. Serial No. 113,603.

To all whom it may concern:

Be it known that I, ROBERT M. LAMPMAN, a subject of the King of Great Britain, residing at Ancaster, in the county of Wentworth and the Province of Ontario, Canada, have invented new and useful Forward and Reverse Gearing Mechanism, of which the following is a specification.

My invention relates to improvements in forward and reverse gearing mechanism especially adapted for operating hoisting machinery, but may be applied to other and various purposes if desired, and consists essentially of a base and frame, a drum journaled in the frame and operated by means of a system of beveled gearing, a clutch for the purpose of reversing the drum, together with novel means for shifting the clutch.

20 The invention has for its objects, first, to provide a machine of the specified class which will quickly and efficiently respond to the operator thereof, and second, to afford facilities whereby the operation of the machine may be effectively accomplished from a distance.

I attain these objects by the mechanism illustrated in the accompanying drawing, in which:

30 Figure 1 is a plan of the entire machine, showing the drum devoid of rope, Fig. 2 is a side elevation of the same, showing the rope attached and wound on the drum, and the clutch in one operating position, Fig. 3 is an enlarged, detailed top view of the drum operating machinery, showing the clutch in neutral position, Fig. 4 is an enlarged detailed side view of the clutch and levers in neutral position, and Fig. 5 is an 40 end view of Fig. 4.

Similar characters of reference refer to similar parts throughout the several views.

Reference being had to the accompanying drawing, the base pieces A, B and C, and the 45 cross pieces D, E, and F, constitute the framework of the machine, H is a horizontal shaft, journaled longitudinally in the bearings 2, which bearings are substantially mounted and secured to the respective cross 50 pieces D, E and F, and J, is a horizontal shaft, journaled transverse of the machine in the bearings 3 which are mounted on and secured respectively to the base pieces A and B.

55 A drum 4 with flanges 5 is rigidly secured to the shaft H between the cross pieces E

and F, and is adapted to wind and unwind a length of rope 6. One end of said rope is secured to the drum 4, and the opposite end passes upward and over pulley wheels, 7 60 and 8 which are usually mounted in the loft of a barn or other structure, and form part of a hoisting apparatus.

The said hoisting apparatus is old and forms no part of my invention, hence is not 65 shown in the drawing. K and L are bevel gear wheels loosely journaled on the shaft H between the cross pieces D and E, and are operated by means of a larger bevel gear wheel M which meshes therewith, and which 70 is rigidly secured to one end of the shaft J as illustrated. The wheel M is operated by means of power delivered to a drive wheel N, which wheel is rigidly secured to the outer 75 end of the shaft J.

A reversible clutch arrangement on the shaft H between the gear wheels K and L, is adapted to regulate and control the winding drum 4, and is clearly illustrated in detail in Figs. 3, 4 and 5 of the drawing. The 80 said clutch consists of a central part 9, adapted to slide in each direction on the shaft 4 by means of a lever P, and end parts 10 and 12 which are rigidly secured to the gear wheels K and L respectively, and form 85 part of the same, and continuously rotate therewith.

The portion of the shaft H between the end parts 10 and 12 of the clutch, is provided with an integral or detachable longitudinal rib 13, which rib fits into a respective groove in the core of the central part 9 of the clutch, hence the shaft H must revolve with the said part 9 of the clutch.

While the work is being carried on, the 90 gear wheels K, L and M are continuously revolving, and it is apparent that the wheel K revolves in the opposite direction to the wheel L. Therefore, when the central part 9 of the clutch is shifted from neutral, as 100 shown in Fig. 3 of the drawing, in connection with the end part 10 of the clutch as shown in broken lines in Fig. 2 of the drawing, the drum 4 turns in the direction to wind the rope; and when it is shifted into 105 connection with the end part 12 of the clutch, the drum turns in the direction to unwind the rope. It will be apparent that when the central part 9 of the clutch is at neutral, the drum will be stationary.

110 The clutch shift lever P is fulcrumed to a bearing 14 which is rigidly secured to the

floor, or to the lower part of the frame; and is pivotally connected at each side to a ring 15, shown in Fig. 5 of the drawing. The said ring fits loosely in an annular 5 groove in the central part 9 of the clutch. This arrangement is adapted to afford sufficient leverage to said part 9, at the same time permitting it to freely revolve.

A partial covering is built over the gear 10 and clutch, consisting of ends 16, sides 17, and top 18.

To afford means for retaining the center part 9 of clutch in neutral position when the machine is required to be idle, but that 15 will not prohibit it from engaging with the end parts 10 and 12 of the clutch when desired, I employ two auxiliary levers 19 pivotally connected one on each side to the lever P. When the clutch is neutral, the 20 levers P and 19 are perpendicularly disposed and parallel each to the other. The said levers extend through and are slideable in respective slots 22 in a plate 21 in the top 18 of the frame. The central ends of 25 the slots 22 through which each a lever 19 passes, terminate in proximity to the central part of the plate 21, the opposite ends of said slots extending each in opposite directions, and terminate one in alinement 30 with each termination of the central slot. Hence, when the clutch is neutral, the levers 19 are in contact one with the central end of one outer slot, and one with the central end of the other outer slot. Therefore it 35 can be seen that when the lever P together with one of the levers 19 is drawn in one direction, the other lever 19 is not permitted to pass the central end of its respective slot 22, hence it tends to tension the 40 other said levers toward neutral position, and when said levers are loosened, they immediately resume neutral position. In order to enable the clutch to be shifted by means of the auxiliary levers 19, lateral stop members 45 23 are secured to the lever P and adapted to engage with their respective lever 19 when the same is drawn over into contact therewith, thereby drawing the lever P with it.

50 A series of ropes or cords 24 are secured to the upper ends of the corresponding levers 19 and P, in order that the machine may be operated by the same person who is attending to the machine or apparatus which 55 is being operated by my invention.

The cords, which are adapted to shift the levers in the opposite direction to the op-

erator, are passed around pulleys 25 which are secured to the upper end part of a vertical post 26, which post is rigidly secured 60 to the end 16, of the covering as shown.

Having fully described my invention, what I claim and desire to secure by Letters Patent, is:—

1. In forward and reverse gear mechanism, a first shaft, a second shaft, a gear secured to the first shaft, pinions provided with clutch portions loose on the second shaft and meshing with the gear on the first shaft, an intermediate clutch member 65 splined to the second shaft and adapted to engage the pinion clutch portions, a plate having a central slot and two parallel lateral slots, one end of each lateral slot terminating in transverse alinement with the 70 corresponding end of the central slot, and the opposite end of the lateral slots terminating in proximity to the middle part of the central slot, a shifting lever loosely connected to the said clutch member, fulcrumed 75 beyond the same and extending through and slideable in said central slot, lateral auxiliary levers pivotally connected to said shifting lever and extending through and slideable one in each said lateral slot, lateral 80 stop members secured to said shifting lever and adapted to engage each a lateral lever, 85 for the purpose specified.

2. In forward and reverse gear mechanism, a first shaft, a second shaft, a gear secured to 90 the first shaft, pinions provided with clutch portions loose on the second shaft and meshing with the gear on the first shaft, an intermediate clutch member splined to the second shaft and adapted to engage the 95 pinion clutch portions, a plate having a central slot and two parallel lateral slots, one end of each lateral slot terminating in transverse alinement with the corresponding end of the central slot, and the opposite ends of the lateral slots terminating in proximity to the middle part of the central part, a shifting lever loosely connected to the splined clutch member, fulcrumed beyond the same and extending through and slideable in said central 100 slot, lateral auxiliary levers pivotally connected to said shifting lever and extending through and slideable one in each said lateral slot, lateral stop members secured to said shifting lever and adapted to engage each 105 a lateral lever, and a series of ropes connected to said levers, as and for the purpose set forth.

ROBERT M. LAMPMAN.
